UNITED STATES PATENT OFFICE

111,043

DESIGN FOR AN AIRPLANE

Alexander P. de Seversky, Asharoken Beach,
Northport, N. Y., assignor to Seversky Air-
craft Corporation, Farmingdale, N. Y., a corpo-
ration of Delaware

Application November 9, 1937, Serial No. 72,719

Term of patent 14 years

To all whom it may concern:

Be it known that, I, Alexander P. de Seversky, residing at Asharoken Beach, Northport, Suffolk County, N. Y., have invented a new, original, and ornamental Design for Airplanes, of which the following is a specification, reference being had to the accompanying drawings, forming a part thereof.

In these drawings,

Fig. 1 is a front elevational view of an airplane showing my new design;

Fig. 2 is a three-quarters rear view thereof;

Fig. 3 is a top plan view thereof, and

Fig. 4 is a side elevation thereof.

I claim:

The ornamental design for an airplane, substantially as shown.

ALEXANDER P. DE SEVERSKY.
